United States Patent Office.

SAMUEL A. WHITNEY, OF GLASSBORO, NEW JERSEY.

Design No. 2,652, dated May 14, 1867.

DESIGN FOR A BOTTLE.

The Schedule referred to in these Letters Patent and making part of the same.

TO ALL WHOM IT MAY CONCERN:

Be it known that I, SAMUEL A. WHITNEY, of Glassboro, county of Gloucester, State of New Jersey, have invented or produced a new and original Design for a Bottle; and I do hereby declare the accompanying drawing, with the following explanation of the same, to form a full, clear, and exact description of the said design.

The figure in the drawing represents an exterior view of the bottle, A being the body, and B the neck of the same.

The body of the bottle is widest at the line *a a*, from whence it gradually tapers towards the bottom. From this line *a a* the body of the bottle is rounded to the line *b b*, where it meets the neck, the latter being slightly flaring, as shown in the drawing, and having the outlines *x x x* representing the outline of the bottle.

I claim the design for a bottle as represented by the outline *x x* in the accompanying drawing.

In testimony whereof I have signed my name to this specification in the presence of two subscribing witnesses.

S. A. WHITNEY.

Witnesses:

JOHN WHITE,
W. J. R. DELANY.
